UNITED STATES PATENT OFFICE.

ARTHUR K. BECKWITH, OF DOWAGIAC, MICHIGAN.

DESIGN FOR A HEATING-STOVE.

No. 38,777.

Specification for Design.

Patented Aug. 27, 1907.

Application filed July 15, 1907. Serial No. 383,949. Term of patent 14 years.

To all whom it may concern:

Be it known that I, ARTHUR K. BECKWITH, a citizen of the United States, residing at the city of Dowagiac, in the county of Cass and State of Michigan, have invented a new, original, and ornamental Design for Heating-Stoves.

My new, original and ornamental design for a heating stove is clearly illustrated in the

accompanying drawing, which is an elevation view thereof.

I claim:

The ornamental design for a heating stove, as shown.

ARTHUR K. BECKWITH.

Witnesses:

J. O. BECRAFT,
HARRY W. PALMER.
